OIL GRADE INDICATOR

Frank J. Philippbar, Bradford, Pa.

Application June 16, 1934, Serial No. 730,952

15 Claims.

(Cl. 40—70)

This invention relates to indicating appliances and more particularly to one for designating the proper grade of oil to be used in a certain make of motor car of ascertained model and mileage. 5 The ordinary chart from which the proper oil grade is found, is of necessity difficult to read due to the great number of factors which must be taken into consideration in reaching the final result. Errors inadvertently occur in reading 10 such charts because of the difficulty of focusing the attention on the separate factors involved in the ultimate determination. With such charts there is present the added disadvantage that to check the final result reached, the same hazardous steps must be repeated, at any point of which a mistake can easily be made.

An object of the present invention is to simplify the determination of the proper grade of oil for a particular motor car and thereby minimize chances for error. 20

Another object is to focus the user's attention on the particular factors involved to the exclusion of those which are inconsequential.

A further object is to expedite the steps of 25 determining the proper oil grade.

A still further object of the invention is to facilitate rechecking of the result found.

Other objects will hereinafter appear.

In the drawing showing a preferred embodiment of the invention:

Figure 1 is a plan view having portions broken away to better show the structure.

Fig. 2 is a plan view with the parts in a different relative position from Fig. 1.

Fig. 3 is a section on the line 3—3 of Fig. 1 on an enlarged scale.

Fig. 4 is a fragmentary view showing the base discs in changed relation from Fig. 1.

In general, the indicating appliance consists of a base part 1 on which the ultimate result is to be indicated and shiftable parts indicated at 2 carried by the base and which when set in accordance with predetermined data point to the final result.

As here shown the shiftable parts 2 include a main carrier member 3 having a pivotal connection at 4 with the base. The carrier member 3 has a pointer at 5 which may be set opposite the proper point on scale 6 marked on the base, corresponding to the year model of the motor car in question. This setting constitutes a base position from which a subsequent setting is made.

Pivotal connected at 8 to the carrier member 3, as here shown, adjacent the pointer end thereof, is an index member 7. The index of this

member 7 is an opening 9 intermediate of its length, through which informational data 10 marked on the base can be read. The angular setting of member 7 relative to carrier member 3 corresponds to the mileage of the motor car in question. To determine this angular setting, an arm 12 is provided which connects the outer end of the member 7 and the pivotal end of carrier member 3. In the illustrated form of the appliance the pivot pin 4 serves to pivotally connect arm 12 to the carrier member 3. The connected ends of index member 7 and arm 12 have a pin and slot connection, the pin 13 being carried by member 7 and the slot 14 being formed in arm 12. This slot 14 is graduated as to mileage. 15

In setting the pin 13 at the point along slot 14 corresponding to the car mileage, the index member 7 will be swung about its pivot pin 8 and the opening 9 will assume a definite position relative to carrier member 3. It will be noted 20 that the pivot points 4, 8 and 13 represent vertices of a triangle of which two sides 4—8 and 8—13 are fixed while the third side 4—13 is variable. The angular dimension of the angle 4—8—13 and correspondingly the angular position of index member 7 relative to carrier member 3 is directly proportional to the length of side 4—13 or the distance between points 4 and 13. For this reason the index opening 9 will be brought to a definite position relative to the carrier member when pin 13 is set at the proper 30 reading along slot 14.

The zero point along slot 14 is so located as to bring pin 13 in the line of centers between pins 4 and 8 when the pin 13 is at the zero point of the 35 slot. The slot 14 projects in a direction away from a line joining pins 4 and 8 as is clear from Fig. 1 of the drawing.

The informational data 10 below the path of movement of the index opening 9 is curved 40 to lie on an arc about pivot pin 4. This data shows the proper oil grade to be used as determined by the settings of the several members. If desired this data could be for a particular make of motor car in which case this data would be 45 unchangeable.

However, in order that the appliance will have wider application, means are provided whereby a set of oil grade readings proper for each different make of car may be brought under the 50 path of movement of opening 9. This is accomplished by forming an opening 15 through the discs 16 to which the pivot pin 4 is connected, this opening 15 lying in the path of movement of index opening 9 and through which the read- 55

ings 10 may be made. Various sets of oil grades each corresponding to a particular make of car may then be brought under opening 15. These sets of oil grades are marked on a disc 17 also carrying the car names at 18 which are viewable through opening 19 in disc 16. In the present device, the discs 16 and 17 are pivotally connected by pin 20 at their centers to enable the desired oil scale 10 for a particular car to be brought in position.

As shown in Fig. 3 the under sides of the carrier member 3 and arm 12 are recessed to accommodate the indicator member 7 and provide a flush under surface.

15 In using the appliance, the following procedure may conveniently be employed. The name of the motor car in question is first brought to opening 19 by relatively rotating discs 16 and 17. Next pointer 5 is brought to the reading on scale 6 corresponding to the car model and held in that position, while the pin 13 is then shifted along the slot 14 to the car mileage as shown in Fig. 2. The oil grade is then read through openings 9 and 15.

25 Since but one oil scale is exposed, likelihood of error is precluded. To check the final result a glance at the several settings is sufficient and no manipulative steps are required.

The face of disc 16 carries printed instructions 30 at 21 pointing out among other features, allowances to be made in cases of extreme temperatures, repairs to the motor car, high speeds, etc.

I claim:

1. An indicating appliance for designating the 35 grade of oil to be used in motor cars of various makes, models, and mileage, comprising motor car make indicia means for indicating the make of motor car, car model indicia means for indicating the model of said make, car mileage indicia means capable of adjustment for indicating the mileage of said motor car, oil grade scale for indicating different grades of oil, and oil grade index means to be set in position along the oil grade scale by and in accordance with the setting of the model and mileage indicators for designating the particular oil grade proper for the car of the model and mileage corresponding to the setting, substantially as described.

2. An indicating appliance for designating the 50 grade of oil to be used in motor cars of various makes, models, and mileage, comprising means for indicating the make of motor car, means for indicating the model of said make, means capable of adjustment for indicating the mileage of said motor car, scale means for indicating different grades of oil, and oil grade index means to be set in position along the oil grade scale, by and in accordance with the setting of the model and mileage indicators, said means for designating the make of car comprising a member having a display opening therein, and a second member bearing the names of the different makes, said members being relatively movable to bring the names of the cars to the display opening, said oil grade scale means consisting of a separate scale for each make of car, arranged adjacent the name thereof, and brought to the display opening at the same time with the name of the car.

3. Apparatus of the class described comprising 70 a front member, having a display opening, a rear member bearing the names of the makes of cars, and also bearing an oil grade scale, one for each name, to be displayed seriatim through the display opening of the front member, an adjustable index and scale on the front member to indicate

the year model of the car, an adjustable index, and a scale to indicate the mileage of the car, a carrier for the said mileage index and scale movably mounted on said front member, and an index for the oil grade scale, set automatically by the setting of the year model index and the mileage index, substantially as described. 5

4. Apparatus of the class described comprising an oil grade scale, a car model scale and an adjustable index to indicate the year model of the 10 car, a car mileage scale and a movable index for indicating mileage of the car, and an oil grade index connected with both the year model index and the mileage index to be set along the oil grade scale by the setting of the said year model index 15 and the mileage index, and thereby designating the particular oil grade proper for the car of the model and mileage corresponding to the setting, substantially as described.

5. Apparatus of the class described comprising 20 an oil grade scale, a scale and an adjustable index to indicate the year model of the car, a scale and a movable index for indicating mileage of the car, an oil grade index connected with the year model index and the mileage index to be set 25 along the oil grade scale by the setting of the said year model index and the mileage index, and a movable member on which the mileage index and mileage scale are carried.

6. Apparatus of the class described comprising 30 an oil grade scale, a scale and an adjustable index to indicate the year model of the car, a scale and a movable index for indicating mileage of the car, an oil grade index connected with the year model index and the mileage index to be set along 35 the oil grade scale by the setting of the said year model index and the mileage index, and a movable member on which the mileage index and scale are carried and a link on which is carried the oil grade index. 40

7. Apparatus of the class described comprising an oil grade scale, a scale and an adjustable index to indicate the year model of the car, a scale and a movable index for indicating mileage of the car, an oil grade index connected with the year 45 model index and the mileage index to be set along the oil grade scale by the setting of the said year model index and the mileage index, and a pivotally mounted member on which the mileage index and its scale are carried, said member having 50 a guideway for the mileage index to control the movement thereof and of the oil grade index, substantially as described.

8. An indicating appliance for designating the 55 grade of oil to be used in a certain make of motor car of ascertained model and mileage, comprising an oil grade scale, a carrier member movable relative to the oil scale, scale means for determining the position of the carrier member corresponding to the ascertained model, an indicator 60 member carried by and movable relative to said carrier member, and scale means for determining the position of the indicator member relative to the carrier member corresponding to the ascertained mileage, said indicator member having 65 index means registering with the oil grade scale.

9. An indicating appliance according to claim 8 in which the indicator member is pivotally connected to the carrier member and the mileage scale means determines the angular position of 70 the indicator member relative to the carrier member.

10. An indicating appliance according to claim 8 in which the indicator member is pivotally connected to the carrier member and the mileage 75

scale means determines the angular position of the indicator member relative to the carrier member, and an arm associated with the carrier member and bearing the mileage scale.

5. 11. An indicating appliance according to claim 8 in which the indicator member is pivotally connected to the carrier member and the mileage scale means determines the angular position of the indicator member relative to the carrier member, and an arm pivotally connected to the carrier member and having a pin and slot connection with the indicator member, the mileage scale being along the slot.

10. 12. An indicating appliance for designating the grade of oil to be used in a certain make of motor car of ascertained model and mileage, comprising a base, an oil grade scale and a model scale on the base, a carrier member having a pivotal connection with the base and having a pointer movable along said model scale, an indicating member having a pivotal connection with the carrier member adjacent the pointer thereon, an arm pivotally carried by the pivotal connection between the carrier member and the base and having a slot graduated by a mileage scale, said indicating member having a pin engaging with said slot and settable along said scale to vary the angular relation between the indicating member and

the carrier member, and an index on the indicator member registering with the oil grade scale.

13. Apparatus according to claim 12 in which the index is intermediate said pin and the pivotal connection of the indicating member and the carrier member.

14. Apparatus according to claim 12 in which the zero position of the slot lies substantially on the line joining said pivotal connections when the pin is at the zero portion of the slot.

15. An oil grade indicator comprising a base carrying a motor car name and for each car a single scale of oil grades suitable for different models and mileages of cars of that particular make of car, a carrier member movable relative to the base member in the general direction of extent of said oil scale, and an indicator carried by the carrier member and movable relative to the carrier member also in the general direction of extent of the oil scale, said indicator member having an index for indicating a proper oil grade on said oil grade scale, and a mileage scale and a model scale, one of which is located to determine the position of the carrier member relative to the base, and the other of which is located to determine the position of the indicator member relative to the carrier member.
